UNITED STATES PATENT OFFICE.

LLOYD I. WILMANS, OF IRVING, TEXAS.

LINE-TYPE-CASTING MACHINE.

1,320,951.

Specification of Letters Patent.

Patented Nov. 4, 1919.

Application filed June 11, 1919. Serial No. 303,446.

To all whom it may concern:

Be it known that I, LLOYD I. WILMANS, a citizen of the United States, residing in Irving, county of Dallas, and State of Texas, have invented certain new and useful Improvements in Line-Type-Casting Machines, of which the following is a specification.

This invention relates to machines of the kind commonly called linotype machines which cast lines of type on slugs or bars formed in molds from metal supplied by a melting pot. It has long been the practice to supply a melting pot with metal by dropping slugs by hand into the pot after they have been used, and various devices have been suggested for automatically feeding or delivering slugs, ingots, or billets of metal to the pot as often as needed to maintain the level of molten metal therein.

My U. S. Patents No. 1,238,972 of Sept. 4, 1917 and No. 1,258,171 of March 5, 1918 show machines of this kind. In said patents I have shown a two-part magazine so mounted that it may be moved from a vertical to a horizontal position or vice versa and provided with a spring pressed gate past which the slugs are delivered by novel ejector mechanism, the operation of which is controlled in one case by thermostatic devices, and in the other by a float operatively connected with the ejector mechanism. My present invention relates to certain improvements on the machines shown in my aforesaid patents, and consists in improved devices for protecting the float from the descending bars or slugs, novel devices for controlling the action of the float on the ejector mechanism, a new way of arranging the driving mechanism of the ejector, a slugs magazine of improved construction, novel devices for controlling the discharge of slugs from the magazine, novel means for locking the magazine to the machine frame, and improved devices for holding the slugs evenly in the magazine during their descent.

The nature of my improvements will be hereinafter more fully described.

50 In the accompanying drawings:—

Figure 1 is a view partly in side elevation

and partly in section of portions of a machine embodying my improvements for feeding metal to the melting pot of a line-type casting machine and indicates how the 55 feeder is applied to the frame of the casting machine.

Fig. 2 shows a vertical section on the line 2—2 of Fig. 4.

Fig. 3 is a view partly in rear elevation, 60 partly in section, and with parts broken away of the improved feeder.

Fig. 4 shows a section on the line 4—4 of Fig. 2.

Fig. 5 is a view on an enlarged scale and 65 in vertical section showing particularly how the slugs magazine is supported and how it may be divided and opened for the purpose of being filled.

Fig. 6 shows a transverse section of the 70 magazine.

Fig. 7 is a detail view on an enlarged scale illustrating particularly the mechanism for holding open the spring gate to prevent the crowding or jamming of the slugs 75 in the magazine.

Fig. 8 shows a transverse section of the magazine on the line 8—8 of Fig. 9.

Fig. 9 is a detail view in rear elevation of 80 a portion of the slugs magazine, indicating the operation of the weight which rests on the slugs and insures their regular descent.

Fig. 10 is a perspective view of the float protector.

Fig. 11 is a detail view of the devices for 85 locking the magazine to the machine frame.

In the drawings I have shown my improvements applied to a well known form of linotype casting machine, but it will be understood that my invention may be embodied in what are known as inter-type machines and also in other machines of the same general kind in which slugs or bars are cast from metal supplied by a melting pot forming part of the machine. 90

It will be apparent from an inspection of the drawings that the machine embodying my present improvements is similar in many respects to those shown in my before-mentioned patents. 95

A portion of the frame of the casting machine is shown at A, and B indicates a

melting pot which may be supported in the usual way. b indicates a part of the hinge of the pot lid.

That part of the machine in which the slugs feeding mechanism is contained is removably supported on the frame of the casting machine, preferably in the manner indicated in Figs. 1, 2 and 3 by a set screw c . The frame of the feeder is indicated by the letter C , and this is of somewhat different construction from those previously employed. In the case of my former patents, certain parts of the train of gears for operating the ejector mechanism were located within the casing, but in order to adapt my machine to accommodate electrical pot heaters, I have changed the construction of the frame and have modified the gearing in the manner presently described. The frame or casing C is preferably provided with a removable lid C' .

The stud shaft d carries a spur wheel D , which may be geared to the mechanism of the casting machine. The shaft d also carries a pinion d' , meshing with a spur wheel E , in turn connecting with a toothed wheel F of the same size and which is secured to the shaft G carrying a crank wheel H which is connected in the manner hereinafter described to the ejector mechanism. The stud shaft d is supported on a bracket I formed with or attached to the casing C , and the stud shaft e of the spur wheel E is also supported on said bracket. This bracket I is located outside the casing and the gears D , E and F are also located outside the casing while the crank wheel H is within the casing but at a considerable elevation above the top of the melting pot.

The pot B may be of ordinary construction, preferably similar to those shown in my former patents, and as in my patent of March 5, 1918, I employ a float B' for controlling the operation of the ejector mechanism. It will be observed that the float proper is adjustably secured to the end of the float rod b^2 by means of a threaded connection and a box nut b^3 . In this way the action of the ejector may be controlled and regulated, and as hereinafter described I also provide other devices for this purpose more directly associated with the ejector mechanism. In order to prevent metal from freezing to the float, I provide means for heating it adjacent the float which may be similar to those shown in my patent of March 5, 1918.

In the accompanying drawings 53 indicates pipes for conveying gas into the pot and delivering it near the float. These pipes 53 and the float rod b^2 are supported at their inner ends by a supporting device 54 similar to that shown in my patent of March 5, 1918, and operating in a similar way.

Other devices, of course, may be employed for heating the metal in proximity to the float.

Before describing the operation of the ejector, I will explain the improvements which I have made in the construction of the slugs magazine. As heretofore, the magazine is made in two parts, a front part J and a rear part K . The front part consists of a plate j attached to two upright frame bars j' , j^2 . The front plate j extends from the top of the magazine to the point j^3 and below this point the front of the magazine is closed by a gate or gates as shown in my patent of March 5, 1918. Preferably two gates L and M are employed, the upper one L being connected to the plate j by a spring hinge l , and the lower one M being connected to the gate L by a spring hinge m .

The two-part magazine is supported by a cross bar N and by a portion of the frame or casing below the magazine. N' indicates a cross bar or brace below the magazine. The front section J carries at its lower end hinge members or brackets O which rest on the cross bar N , and the section K carries hinge members or brackets O' which also rest on said cross bar. The arrangement is such that the rear portion of the magazine may be turned backward to a horizontal position as indicated in Fig. 5 for the purpose of filling it with slugs, without moving the front part, or both sections of the magazine may be turned to a horizontal position and then removed from the machine in order to obtain free access to the melting pot. This feature of the machine is fully described in my former patents.

The rear section K comprises a plate k which is secured to the upright frame bars k' , k^2 . This plate k is arranged at the lower end of the magazine, while the upper portion of the rear section is closed by a panel k^3 of transparent material, such as glass. This is for the purpose of allowing the slugs to be inspected. In this way one can see at a glance at any time the condition of the slugs, whether they are low or are inclined to tip over or in other ways become disarranged. The glass panel may be secured in place in any suitable way. The plate k , as heretofore, carries the fingers k^4 on which the slugs rest and between which the ejector teeth operate.

The rear section K is equipped with plates P . These plates are countersunk in the frame bars k' , k^2 and they support rollers p' pivoted at p and which are adapted to engage the lower edge of the gate M when the rear section K is turned rearward. The frame bars j' , j^2 of the front section are cut away as indicated at j^4 to allow free passage of the rollers.

It has been found that sometimes the

slugs follow the movement of the ejected slugs or ride them so as to project part way out of the magazine and these slugs seat themselves on the fingers k^4 and project past the front of the gate M so that when the magazine is swung open, that is when the rear part of the magazine is swung backward, the partly ejected slugs strike the bottom of the gate and either lock the magazine and prevent its free opening or bend the fingers. In some cases the slugs become jumbled in the bottom of the magazine, but the devices above described overcome these difficulties, as when the rear section of the magazine is swung open the rollers p force the gate open and the partly ejected slugs cannot then come in contact with the gate.

In order to lock the magazine in upright position, I apply a locking lever Q which is pivoted to the frame at q and carries at its outer end a locking device illustrated in detail in Fig. 11. As there shown the lever Q is formed with an enlarged end or head q' which receives the shank r of a locking block r' , which is pivotally connected with the head at r^2 . By means of a handle or thumb piece r^3 the block may be turned to open or closed position. As shown in Fig. 1, the lever is engaged with a pin or screw R on the front section of the magazine and the rear section of the magazine is connected with the front section by the guiding and locking devices S , so that the magazine as a whole is held firmly in upright position. When in this condition the rear section may be moved to a horizontal position without moving the front section, as the devices S readily permit this, but when it is desired to remove both sections of the magazine from the frame, the lever is unlocked and withdrawn from the magazine by turning the thumb piece or handle r^3 until it is free from the locking screw or pin R , and then the lever may be swung upward and away from the magazine. When the magazine has been removed and replaced to its operative position, the locking lever may be very quickly and automatically connected with it, inasmuch as the locking block r' has an inclined portion r^4 which engages the locking screw in such manner as to swing the locking block about its axis while the lever is being lowered, and then the block automatically moves to a position below the screw and thus securely connects the lever with the magazine.

The devices S referred to are illustrated in Fig. 6. One of these devices comprises a plate s which is secured to one of the frame bars on the front section of the magazine and is provided with a beveled or inclined edge s' . The plate s has some elasticity so as to yield sidewise when the two sections

are being brought together. The other locking device comprises a plate s^2 which is attached to the opposite frame piece j^2 and projects rearwardly therefrom. This plate is provided with a shoulder or inclined locking end s^3 , and the arrangement is such that when the rear section of the magazine is swung to an upright position, it engages the devices S which serve to guide the rear section into proper relation to the front section and to then lock them in place. The locking device may readily be released when desired.

It sometimes happens when the magazine contains a single column of slugs that the top slugs crawl and descend endwise in the magazine. This is caused by the constant vibration of the magazine due to the operation of the casting machine with which it is connected. To overcome this trouble I provide a weight or follower which is arranged in the magazine on top of the pile of slugs and exerts a constant pressure thereon and descends as the pile lowers. This follower is preferably of the kind shown in Figs. 8 and 9 and comprises a body portion T , having enlarged ends or arms t carrying rollers t' , there preferably being two rollers at each end, arranged one above the other and bearing against the side of the magazine. Each arm t extends vertically above or below the body T , and the rollers are so spaced as to prevent the follower from tipping or otherwise moving out of a true horizontal position so as to exert an even downward pressure on the slugs. The body T is formed at its middle portion with arms t^2 , t^3 which project upward and downward from the follower, the lower arms resting on the slugs X as indicated in Fig. 9. It will be observed that the follower is so shaped that if desired it may be reversed or turned over. It may also be reversed by being turned end for end. The arms t , t^2 , t^3 are so spaced as to allow free movement of the ejector teeth when the follower is in the lower part of the magazine.

In my patents before referred to I have shown aprons or shields extending from the slugs magazine into the melting pot for the purpose of guiding the slugs and for shielding or protecting the thermostatic devices and the float contained in the pot. In both cases the apron was attached to the frame of the feeder and it was necessary to remove the feeder bodily when it was desired to skim dross from the molten metal. In both cases also the apron was rigidly secured to the feeder frame and had no movement independently thereof. Sometimes large slugs would get under the apron and owing to the usual forward and upward movement of the pot, the apron would sometimes be bent out of position. To overcome these difficulties

I have provided an apron or shield of improved construction and mounted in a new way. This apron or shield I now prefer to call a float protector as one of its principal objects is to prevent the float from injury or interference by slugs or pieces of metal as they drop into the melting pot.

Fig. 10 shows the float protector detached from the feeder. It comprises a body portion U, having a downwardly extending inclined front portion u serving as a shield or protector for the float and also a guide for the slugs. The upper part of the body is turned backward to form a top portion u⁶, which as shown in Fig. 2 is disposed below the magazine when the protector is in place. At each end the protector is provided with rearwardly extending arms u', having open bearings u² which are adapted to fit over studs or projections V on the frame or casting. At one end the protector is provided with an arm or handle u³ by means of which it may be removed. The protector is suitably shaped at u⁴ to fit parts of the machine with which it is connected. Preferably the protector is made of a single piece of sheet metal bent to shape, as shown, the handle u³ being preferably made of a separate piece secured to the protector as indicated.

The protector is mounted in the manner indicated in Figs. 1 and 2, the arms u' resting on the studs V, while the upper edges of the arms bear against the under sides of the brackets O of the front portion of the magazine. In this way the arms are prevented from rising from the studs, but a pivotal connection is provided in order that the protector may swing to a slight extent to follow the swinging movement of the pot. When it is desired to skim dross from the molten metal, the two sections of the magazine may be removed and then the protector may, by means of the handle u³, be lifted and removed.

It will be observed that the arms u' are rounded at u⁵ so that the protector is free to rock to a sufficient extent, and yet as the arms bear against the brackets O, the protector cannot be lifted off from the studs when the magazine is closed.

The ejector mechanism is in general of the same kind as that shown in my prior patents. An ejector carriage W reciprocates in guides w in the feeder frame and it carries teeth w' which are adapted to engage one or more slugs in the bottom of the magazine. These teeth operate between the fingers k⁴ of the magazine and the ejector teeth are adapted to pass entirely across the lower portion of the magazine as indicated in Fig. 7.

The ejector carriage is operated by an arm Y connected at its rear end to a crank pin h on the crank wheel H secured to the shaft G before referred to. The front end

of the arm Y is adapted to engage teeth w² 65 on the carriage and when so engaged the carriage is moved forward by the arm, but if the arm is raised in such manner that it does not engage the teeth w², the front end of the arm will ride over the teeth and will enter a 70 recess w⁵ in the toothed portion of the carriage. This operation is similar to that shown in my patents.

The headed end of the ejected arm is formed with a downwardly extending lug y' 75 which carries an adjustable screw y² provided with a lock nut y³. The lower end of the set screw rests on a bracket y⁴ carried by the float rod b². When the machine operates to feed slugs to the pot and the float is in a lowered position the screw y² passes over the bracket y⁴ without being influenced thereby and at this time the ejector arm engages the carriage and operates it, but if the pot is full and the feed of slugs is unnecessary, the 80 float is in a raised position and then the bracket y⁴ engages the screw y² and causes the ejector arm to be raised and the feed of slugs to be suspended. By adjusting the screw y², the ejector may be caused to 85 operate in the desired way to correspond with any desired level in the melting pot. The adjustment afforded by the screw y² may be used either separately or in connection with the adjustment of the float on 90 the end of the float rod.

It will be observed that the crank wheel H is located within the feeder casing near the longitudinal center thereof so that it may be connected with the ejector rod which 100 is arranged centrally, but the crank wheel H and its shaft G are arranged considerably above the plane of the melting pot, and the train of gearing which operates the shaft G is outside the casing. It will also be observed that the casing is cut away or opened at the side adjacent the melting pot, thus leaving a clear space in which may be mounted the electric box B⁴ commonly used in connection with the electrically heated 105 pot.

Sometimes the slugs are not fully ejected from the magazine but become jammed between the ejector and the spring gate of the magazine. The pressure of the spring gate 110 forces these jammed slugs against the front of the ejector and they ride back and forth and the jam increases as more slugs are ejected, while the tension of the spring gate becomes greater by reason of the addition 115 of more slugs in the jam. To remove these troubles I have devised means for holding the gate open when the jam is started and to hold it open sufficiently long for the ejector to draw back free from pressure from the spring gate and in such manner as to release the slugs from pressure of the gate 120 and at the same time allow them to fall 125

freely into the melting pot. As soon as they thus fall the spring gate is released and returned to its normal position. The mechanism used for this purpose is extremely simple and is most fully shown in the drawings.

A lever Z is pivotally connected at z to the feeder frame. It extends forward beyond the plane of the magazine and is provided at the front with a toothed head z' which 10 is adapted to engage at times a catch plate z^2 secured to the gate of the magazine. The rear end of the lever is connected with a spring z^3 which tends to draw this end of the lever downward and to raise the front 15 end of the lever. The rear portion of the lever extends over a roller x carried by a screw x' engaging a lug x^2 extending downward from the ejector. It will be observed with reference to Fig. 7 that the under side 20 of the rear portion of the lever is inclined from its rear end upward to the pivot z and this part of the lever is engaged by the roller x . When the ejector is moved forward the roller in connection with the 25 spring causes the rear end of the lever to be lowered and the front toothed end to be raised. This occurs during each reciprocation of the ejector and during each backward stroke of the ejector the front toothed 30 end of the lever is lowered. If the gate M is forced open by an accumulation of slugs, it will engage the toothed end of the lever which will hold the gate open until the slugs have dropped and until the ejector recedes. 35 The arrangement is such that the lever does not engage the gate until the latter is opened in the manner before described.

Experience has demonstrated that by the devices just described all jamming and 40 crowding of the slugs in such manner as to interfere with the operation of the ejector is entirely eliminated.

By my present improvements I have entirely overcome the difficulties encountered in 45 the practical operation of the machines shown in my prior patents. The improved machine operates with great regularity and precision to feed metal to the melting pot as often as required without clogging of the magazine. The magazine can be easily opened 50 without interference by the slugs therein. The slugs are caused to descend in the magazine without crowding and the condition of the slugs can at all times be inspected. The 55 float and heating devices are shielded by a protector which is not liable to be bent or broken and may be readily removed from the pot whenever required. Furthermore the driving mechanism of the ejector is so 60 constructed and arranged that space is provided for parts of an electric heater when such is used in connection with the melting pot.

I claim as my invention:

65 1. A magazine for holding pieces of

metal to be supplied to a melting pot, in combination with a weighted follower within the magazine having enlarged ends bearing against the sides of the magazine and guided thereby.

2. A magazine for holding pieces of metal to be supplied to a melting pot, in combination with a weighted follower having 70 enlarged ends each of which carries rollers arranged one above the other which 75 bear against the sides of the magazine and are guided thereby.

3. A magazine for holding pieces of metal to be supplied to a melting pot, in combination with a weighted follower carrying at 80 its opposite ends rollers which bear against the opposite sides of the magazine.

4. A magazine for holding pieces of metal to be supplied to a melting pot, in combination with a weighted follower having 85 arms at each end extending above and below the body portion of the follower, and centrally arranged arms bearing upon the middle portion of the contents of the magazine.

5. A magazine for holding pieces of metal to be supplied to a melting pot, in combination with a follower having arms at each 90 end extending above and below the body of the follower, and centrally arranged 95 arms bearing on the middle portion of the metal within the magazine, and rollers carried by the arms at the ends of the follower which bear against the sides of the magazine.

6. A magazine for holding pieces of metal to be supplied to a melting pot, consisting of two hinged sections one of which carries a spring-controlled gate and the other rollers which bear against the gate when the roller-carrying section is separated from its 105 companion sections.

7. A magazine for holding pieces of metal to be supplied to a melting pot, comprising a front section carrying a spring-controlled 110 gate and a rear section carrying devices which bear against the gate and press it outward when the rear section is turned to separate it from the front sections.

8. A magazine for holding pieces of metal to be supplied to a melting pot, comprising two separable upright sections one of which is mounted to turn about a horizontal axis and the other of which carries spring catches and guides which automatically engage the 115 hinged section when the latter is turned to upright position.

9. A magazine for holding pieces of metal to be supplied to a melting pot, comprising upright hinged sections provided with a 120 locking member, and a locking lever for holding them in upright position having a head portion engaging the locking member of the magazine and carrying a locking 125 block which automatically engages said 130

locking member and which is provided with a handle for releasing it from said member.

10. The combination with a magazine for holding pieces of metal to be supplied to a melting pot and which is provided with a spring-controlled gate, of an ejector for discharging metal from said magazine past said gate, and means for automatically holding the gate open if the metal crowds or jams in the magazine during the operation of the ejector.

11. In combination with a magazine for holding pieces of metal to be supplied to a melting pot and which is provided with a spring-controlled gate, of an ejector for discharging metal from the magazine past said gate, and means for automatically holding the gate open if metal crowds or jams in the magazine during the operation of the ejector, said last-mentioned means comprising a lever having an outer end adapted to engage the gate and means operated by the ejector for raising and lowering said lever.

12. The combination with a magazine for holding pieces of metal to be supplied to a melting pot and which is provided with a spring-controlled gate, of an ejector for discharging metal from the magazine past the gate, a lever pivotally connected with the machine frame and having an outer end adapted to engage the gate and a spring-controlled inner end, and means carried by the ejector for controlling the movements of said lever.

13. The combination with a magazine for holding pieces of metal to be supplied to a melting pot and which is provided with a spring-controlled gate, of an ejector for discharging metal from the magazine past the gate, a lever pivoted to the machine frame having a toothed front portion and a rear portion formed with an inclined edge, a spring tending to hold the outer end of the lever in an elevated position, and devices carried by the ejector and operating on the rear portion of said lever to control the movement thereof.

14. The combination with a magazine for supplying metal to a melting pot, of an ejector for discharging metal from the magazine into the pot, a power-operated arm for reciprocating said ejector, a float within the pot, a float rod pivotally connected with the machine frame, and an adjustable connection between said rod and the ejector-operating arm.

15. The combination with a magazine for holding pieces of metal to be supplied to a melting pot, of an ejector for discharging metal from the magazine, an ejector-operating arm adapted to be connected to and disconnected from said ejector, an adjustable screw carried by said arm, a float in the melting pot, a float rod pivotally con-

nected with the machine frame, and a bracket carried by said rod adapted to engage said adjustable screw.

16. A machine for feeding metal to a melting pot, comprising a frame or casing associated with the pot and having a clear space adjacent the pot, a magazine for supplying metal to the pot, an ejector for discharging metal from the magazine into the pot, an ejector arm for reciprocating the ejector, a crank wheel in the upper portion of the frame for operating said arm and arranged inside the casing, a shaft to which said wheel is secured and which extends laterally outside of the casing, gearing adapted to be connected with the power mechanism of a type-casting machine and which is located outside the casing at the outer end of said shaft, and means for supporting said gearing.

17. The combination with a magazine for holding pieces of metal to be supplied to a melting pot, of an ejector for discharging metal from the magazine into the pot, a float operatively connected with the ejector for controlling its movements, and a float protector extending from the magazine into the pot above the float and which is pivotally mounted at its upper end.

18. The combination with a magazine for holding pieces of metal to be supplied to a metal pot, of an ejector for discharging metal from the magazine, a float in the melting pot operatively connected with the ejector for controlling its movements, and a float protector extending into the melting pot and which is removably supported at its upper end whereby it may be readily detached to expose the float and the metal in the pot.

19. The combination with a magazine for holding pieces of metal to be supplied to a melting pot, of an ejector for discharging metal into the pot, means of pivotally connecting the sections of the magazine to the frame or casing of the machine, comprising a horizontally arranged rod supporting brackets extending from the magazine sections, a float protector extending into the machine and having arms at its upper end supported on the frame and pivotally connected therewith, said arms having curved portions beneath the brackets of the magazine, the arrangement being such that the float protector is held in place above the float but is permitted to rock on its pivots within limits.

20. A float protector having a body portion providing a shield or apron over which the metal is fed to a melting pot, rearwardly extending arms forward with open bearings and a vertically arranged handle to facilitate in the removal of the protector from its mounting.

21. The combination with a rocking

melting pot and a magazine for holding pieces of metal to be fed to the pot, of means for ejecting metal from the magazine, a float in the pot controlling the operation 5 of the ejector, means for heating the metal in proximity to the float, and a protector extending over the heating means and over the

float which is pivotally mounted and provided with means for removing it from the pot.

In testimony whereof, I have hereunto 10 subscribed my name.

LLOYD I. WILMANS.
